UNITED STATES PATENT OFFICE

2,425,313

DISPENSING DEVICE

Arthur Hammerstein, Palatine, Ill.

Application December 21, 1944, Serial No. 569,153

1 Claim. (Cl. 215—75)

1

The invention relates to dispensing devices and more particularly to devices for dispensing liquids such as perfumes, shaving lotions, and the like from receptacles.

The object of the invention is to provide a dispensing device whereby the expulsion of the liquid from the container may be controlled at will and which is constructed in a simple manner so as to reduce the possibility of dislocation of the parts to a minimum.

The invention contemplates further the provision of a novel and simple dispensing device designed in addition to its other functions to serve as a closure for the receptacle in which the liquid is contained.

A further object of the invention is to provide a simple and novel dispensing device which may be readily sealed at will to prevent unintentional spilling of the contents of the receptacle and to enable the latter and its contents to be carried about, for instance, in a traveling bag without danger of spilling said contents.

Other objects of the invention will appear from the description hereinafter, and the features of novelty will be pointed out in the claim.

In the accompanying drawing, which illustrates an example of the invention without defining its limits,

Fig. 1 is an elevation of a receptacle with the novel dispensing device in place thereon;

Fig. 2 is an enlarged vertical section of the novel dispensing device; and

Fig. 3 is a plan view thereof.

In the illustrated example, the novel dispensing device is shown in the form of a closure for receptacles such as a bottle 5 in which the liquid to be dispensed is contained.

The dispensing device itself comprises a sleeve 6 suitably fixed upon the neck 7 of the bottle or other container 5, said sleeve including an inwardly-directed annular flange 8 which is internally screw-threaded as illustrated in Fig. 2.

The dispensing device further includes a hollow member 9 threaded into the flange 8 and including an annular outwardly-directed flange 10 which projects over the flange 8 of the sleeve 6. If desired, a gasket 11 of suitable resilient or other packing material may be located between the flanges 10 and 8 for preventing leakage at this point.

At its upper end, the member 9 is internally screw-threaded for the reception of an externally-threaded bushing 12 having an outwardly-directed flange 13 adapted to lie in surface engagement with the flange 10. The bushing 12 is in-

2

ternally screw-threaded at least throughout a part of its length as indicated at 14.

A tubular spout 15 extends axially through the bushing 12 in opposite directions and is in screw-threaded engagement with the threads 14 of said bushing 12, and at its inner end, is provided with an annular flange 16 slidably fitting the interior of the member 9 as shown in Fig. 2.

The tubular spout 15 includes an axial passage 17 which terminates at its lower end in a valve-seat 18 located in spaced axial registry with a cooperating valve-seat 19 formed at the inner end of a passage 20 with which the member 9 is provided and which establishes communication between the interior of the latter and the interior of the receptacle 5. A ball-valve 21 is located in the interior of the member 9 and is movable between the valve-seats 18 and 19 for cooperation therewith, in the manner to be described hereinafter, to control the dispensing of the liquid contained in the bottle or other container 5.

In order that the ball valve 21 may always automatically roll into position upon the seat 19 to seal the passage 20, when this is desired, the bottom of the member 9 preferably is inclined toward said passage, for instance, as illustrated in Fig. 2. The inclination may be at any suitable angle to effect the intended result; an angle of 59° has been found to give satisfactory results.

As illustrated in Fig. 2, the parts of the novel dispensing device are adjusted to permit the dispensing of the contents of the bottle or other container 5. As long as the latter remains in an upright position, the ball-valve 21 will remain in place on the valve-seat 19 and thereby seal the opening 20 to prevent evaporation of the contents of said bottle 5 or other unintentional disposal thereof.

In this adjustment of the parts, the valve seat 18 is located at a distance from the valve-seat 19 so that if the bottle 5 or other container is tilted or inverted, the ball-valve 21 will leave the valve-seat 19 and position itself in the interior space of the hollow member 9 between the two valve-seats or said ball-valve may even seat itself upon the valve-seat 18.

To dispense the contents of the bottle 5 or other container, it is simply necessary to move the container or bottle 5 back and forth in a tilted or inverted position. This causes the ball-valve 21 to move about in the interior of the member 9 between the two valve-seats 18 and 19 as will be apparent to thereby enable the contents of the bottle 5 or other container to pass out through the passage 20 into the interior of the member 9.

and thence out to the passage 17 of the dispensing spout 15 in such quantity as may be desired. This is dependent upon the length of time during which the bottle 5 or other container is manipulated as described and may also be regulated by adjusting the spout 15 in the bushing 12 to regulate the distance between the two valve-seats 18 and 19. After a given dispensing operation has been completed, the bottle 5 or other container is returned to the upright position illustrated in Fig. 1 in which the ball-valve 21 automatically reseats itself upon the seat 19 and thereby seals the passage 20 to prevent evaporation and other loss of the contents of said bottle or other receptacle 5.

If it is desired to carry the receptacle 5 with its contents, as, for instance, while traveling from place to place, the novel dispensing device may be adjusted to lock the ball-valve 21 on the seat 19 to thereby prevent any leakage of the contents from the bottle 5 or other receptacle through the passage 20. This is accomplished by adjusting the dispensing spout 15 downwardly in the bushing 12 until the valve-seat 18 firmly engages the ball-valve 21 and clamps it against movement of any kind relatively to the valve-seat 19.

The novel dispensing device may be readily combined with bottles or other receptacles either so as to be removable therefrom at will and thus capable of being reutilized or the device may be permanently secured to the bottle or other receptacle and discarded therewith when the liquid contents have been fully disposed of.

The novel dispensing device is extremely simple in construction and, accordingly, is not likely to easily get out of order and, at the same time, is of maximum efficiency for its intended purposes.

The novel dispensing device may be made of metal or any other suitable materials and is particularly adapted to be made of plastics such as Lucite and the like.

When the novel dispensing device is removably combined with the bottle or other receptacle 5 as illustrated in Fig. 2, the hollow member 9 and its associated elements may readily be removed from the sleeve 6 to permit refilling of the bottle or other receptacle 5 at will.

While the novel device is designed primarily

to control the dispensing of liquids such as perfumes, shaving lotions, and the like, it obviously may be utilized for controlling the ejection of other types of liquids, and in some forms, may be used for controlling the dispensation of other types of materials.

Although the present invention has been described in conjunction with a preferred embodiment, it is to be understood that modifications and variations may be resorted to without departing from the spirit and scope of the invention, as those skilled in the art will readily understand. Such variations and modifications are considered to be within the purview and scope of the claim.

I claim:

A dispensing device of the kind described comprising a sleeve adapted for connection with a receptacle and having an inwardly-directed annular flange internally screw-threaded, a hollow member threaded into said sleeve and having a passage provided with a valve-seat at one end, an internally-threaded bushing threaded into said hollow member, a tubular dispensing spout threaded into said bushing and provided with a valve-seat at its inner end in spaced relation to said first valve-seat, and a ball valve in said hollow member movable between said valve-seats to control ejection of the liquid contents of said receptacle, and automatically returning to one of said seats at the conclusion of an ejecting operation, to seal the receptacle against losses of its contents, said dispensing spout being adjustable to clamp the ball valve between and in sealing engagement with both of said valve-seats to seal the contents in said receptacle.

ARTHUR HAMMERSTEIN.
